Application August 9, 1932, Serial No. 628,037

23 Claims. (Cl. 230—206)

This invention relates to motor-driven compressors suitable for refrigerating machines of the compressor, condenser, expander type, and is more especially concerned with a compressor having a novel and improved oiling system for lubricating the various bearing surfaces, removing oil from the motor chamber and separating the oil from the gas, before the latter reaches the compressor cylinder.

The invention will best be understood by reference to the following description, when taken in connection with the accompanying drawings of one specific embodiment thereof, while its scope will be pointed out more particularly in the appended claims.

In the drawings:

Fig. 1 is a plan of a motor-driven compressor embodying the invention;

Fig. 2 is a vertical, longitudinal section on an enlarged scale, mostly on line 2—2 of Fig. 1;

Fig. 3 is a vertical, sectional view on line 3—3 of Fig. 2;

Fig. 4 is a vertical, sectional view, partly on line 4—4 of Fig. 2;

Fig. 5 is a vertical, sectional view on line 5—5 of Fig. 2;

Fig. 6 is a vertical, sectional view on line 6—6 of Fig. 2;

Fig. 7 is a perspective view of a baffle which assists in separating the oil from the refrigerant and prevents oil from entering the compressor cylinder;

Fig. 8 is a plan, on an enlarged scale, of a sliding shoe or cross-head, which connects the crank-pin to the piston;

Fig. 9 is a horizontal, sectional view, on line 9—9 of Fig. 6;

Fig. 10 is a horizontal, sectional view of the main bearing on line 10—10 of Fig. 3; and

Fig. 11 is a vertical, sectional view, on line 11—11 of Fig. 10.

Referring to the drawings, and to the embodiment of the invention illustrated therein, and having reference at first more particularly to Fig. 6, there is shown a cylinder 20 having a lateral intake port 21, which is covered and uncovered by a piston 22. The charge drawn into the cylinder and compressed by the piston is discharged through openings 23 in a plate 24 having an annular seat 25 for an outlet valve 26, which, as shown, is a thin, wafer-like steel disk, normally urged to its seat by a spring 27 within an outlet chamber 28, formed in a cylinder head 29, and communicating with an outlet passage 30, the latter in practice being connected with a condenser,

In the present example, the cylinder 20 is in the nature of a sleeve or lining, fixedly mounted in a surrounding support, herein a housing 31, having a chamber 32, which encloses part of the driving mechanism.

The driving mechanism, as herein shown, comprises an element such as a crank-pin 33, having an orbital path, and suitably connected to the piston to reciprocate the latter, the connection shown being a shoe or cross-head 34, mounted to slide in a groove 35 extending transversely of the piston, though the invention is not limited to this form of driving connection, but might employ, for example, a connecting rod or pitman.

Turning now to Fig. 2, the crank-pin is driven by a rotatable element, herein a shaft 36 mounted to rotate in a bearing 37 presented by a plate 38, which is in the nature of a wall constituting a cover for the chamber 32, and a partition which separates the latter from a motor chamber 39, also formed in the housing 31, the other end of this motor chamber being closed and sealed by a cover plate 40, thus providing a sealed housing for the entire mechanism. The plate 38 is suitably secured in place, as by cap-screws 41, and the plate 40 is similarly secured in place by cap-screws 42.

The motor chamber 39 houses an electric motor comprising a stator 43 fixed in the housing, and a rotor 44 suitably secured to the shaft 36, as by providing the latter with a reduced portion 45, to which the rotor is secured as by a key 46 and by a nut 47 threaded onto a further reduced portion 48. The nut urges the rotor and a suitable thrust washer 49 toward a shoulder 50 presented by the body of the shaft, said washer resting against the adjacent end of the bearing 37, while running. The rotor is slightly offset axially with relation to the stator in a direction opposite to the bearing, thereby to utilize the magnetic flux to eliminate any tendency of the rotor to move endwise. The stator has three lead wires 51, attached respectively to lead-in plugs 52, two of which are shown in Fig. 1.

The refrigerant to be compressed, instead of entering the chamber 32 directly, enters the motor chamber 39, as by means of a plug 53 (see Fig. 1), threaded into the housing, said plug in practice being connected as usual with an expander. The refrigerant, after entering the motor chamber 39, enters the lower end of a conduit (see Fig. 2) formed partly by a pipe 54 and partly by a passage 55 (see Fig. 4) and a passage 56, both drilled in the cover-plate 38, into a recess 57 (see Fig. 3), which is in effect a part of the

chamber 32. From this chamber, the gaseous refrigerant passes upwardly (see Fig. 6) through passages 58 and 59 drilled in the casing 31, and thence through a port 60 in registration with the 5 lateral intake port 21 of the cylinder 20. Thus, the refrigerant, on its way to the cylinder, passes through the motor chamber, and cools the motor as well as the shaft and its bearing.

So far as the general aspects of the oiling system presently to be described are concerned, the 10 crank-pin 33 might be fixedly secured to the driving shaft 36. In the form shown, however, the crank-pin is connected to the driving shaft by unloading mechanism (see Fig. 2), which in 15 general may be said to impart to the piston a reciprocatory motion of variable amplitude, varying from a zone in which the piston covers and uncovers the lateral intake port and causes gas to be admitted through said port and discharged 20 past the outlet valve, to a zone within which the piston maintains the port closed. In the first zone, a full stroke is imparted to the piston, while in the second zone, the stroke is reduced to one of small amplitude, or if desired, may be reduced 25 to zero. In the form shown, the stroke is reduced to one of small amplitude, the amount of reduction of the stroke being determined by the amount of eccentricity of the oscillatory element now to be described.

The crank-pin which has been referred to as 30 an element having an orbital path is carried by an oscillatory element, herein a rockshaft 61, having an axis of oscillation eccentric to the axis of rotation of the rotatable element, namely: the shaft 36. When, therefore, the rockshaft is 35 turned about its axis, the radius of the orbit of the crank-pin is varied from a radius in which the piston is effective to cover and uncover the lateral intake port of the cylinder to a radius in 40 which the piston is ineffective to uncover said port, and furthermore, this change of radius changes the load of the compressor on the motor from full load in which the piston is at full stroke to a reduced load, or no load at all, depending, 45 as has been stated, upon the location of the axis of the rockshaft. This reduction or total elimination of the load enables the motor to start and to get up speed partially or wholly free from load, and therefore a motor of low starting torque may 50 be employed.

As herein shown, the eccentricity of the rockshaft 61 and the corresponding eccentricity of the crank-pin 33 are governed by a centrifugal governor, which is responsive to variations in the 55 speed of the motor. This is conveniently accomplished by mounting on the rockshaft a centrifugal weight 62 (best shown in Fig. 6), herein formed as an integral part of the rockshaft. The turning movement of the rockshaft in opposite 60 directions is limited by suitable means, such as a stop-screw 63, having a reduced portion 64 which is received in a segmental groove 65 in the rockshaft.

While the weight 62 might be relied upon with 65 out other aid to control the turning of the rockshaft under the influence of variation in the speed of the motor, I prefer to employ a spring 66 to assist the weight. As herein shown, this spring is arranged to have a neutral position, in 70 which it is not stressed, and in which position the stop-screw 63 (see Fig. 6) is in the center of the segmental slot 65 when the machine is at rest. This is simply a matter of securing the ends of the spring in the desired relationship to the parts 75 which they connect. As shown in Fig. 2, one end

of the spring is wound about and secured to a plug 67, having a tongue 68, which is received in a slot 69 in the shaft 36, and the other end of the spring is wound about and secured to a similar plug 70, having a tongue 71 received in a slot 5 72 in the rockshaft 61. As herein shown, these slots are conveniently formed by making drilled holes, into which the tongues extend laterally. In the present example, the rockshaft is mounted in an eccentrically disposed bore 73 in the shaft 10 36, and the spring 66 is disposed in a bore 74 with- 15 in the rockshaft.

In order that the rotating parts shall be in balance after full speed of the motor is attained, I provide the rotatable shaft 36 with a fly-wheel 15 75, having a weight 76 which is opposite to the weight 62 when the latter is fully advanced. This ensures smooth running, without noticeable vibration, as the two weights under this condition 20 constitute together a balanced fly-wheel.

The operation of the unloading mechanism will 25 not be described in detail, because it forms no part of the present invention, except in so far as it is related to the oiling system presently to be described. It will suffice to say that in the initial position of the crank-pin, when the parts are at rest, the crank-pin has a slight throw, or its axis may be coincident with the axis of the rotatable shaft in which position it has no throw at all. When the motor starts and as its speed 30 increases, the eccentricity of the crank-pin increases, until in the full running position shown in Figs. 2 and 6, the piston has its maximum stroke. As herein shown, the spring is set so that it tends to restore the crank-pin to its mid-position, instead of to its position of minimum throw. When the motor starts, the weight 62 will by its inertia lag behind the shaft 36, and will thus bring the crank-pin momentarily to its minimum throw, in opposition to the resistance of 35 the spring. When, however, the shaft acquires sufficient speed, the centrifugal effect of the weight, due to its eccentric mounting, results in the weight being thrown outwardly with relation to the shaft. During the first half of this movement, the spring, which is under stress, assists the weight in moving outwardly with relation to the shaft. 40

As the speed of the shaft increases, the weight carries the rockshaft and the crank-pin past the 45 neutral position of the spring, and thereafter the spring is stressed in the opposite direction, and yieldingly resists outward movement of the weight. When the weight, the rockshaft and the 50 crank-pin reach their extreme outward position, the crank-pin has its greatest throw and the piston its greatest stroke.

When the current is cut off from the motor and the speed of the shaft is reduced, the weight 55 commences to lag behind the shaft, and is assisted by the spring during the first half of this backward movement with relation to the shaft. During this time, the throw of the crank-pin is reduced, the stroke of the piston is correspondingly decreased, and the load on the motor is 60 diminished, inasmuch as the piston has little or no work to do.

The oiling system will now be described, reference being had at first to Fig. 2. A positive pressure circulation of oil is provided by an oil 65 pump having a piston 77, herein conveniently formed as an integral part of the piston 22 and working in a cylinder 78, having a lateral intake port 79, which is covered and uncovered by the piston 77, while the piston has one or more, here- 70 75 80 85 90 95 98

in two, lateral ports 80 (which merely for convenience of manufacture are made separate instead of as a slot), which are brought into registration with the port 79 in the cylinder during the movement of the piston. The lower portion of the chamber 32, or crank-case, constitutes an oil reservoir in which a body of oil is maintained at some such level as that shown in Fig. 2, well above the upper end of the cylinder 78. At this point, it is to be understood that the weight 62 and the fly-wheel 75 with its weight 76, in turning, splash oil about in the chamber 32, and provide additional assurance of lubrication of all running parts within the chamber, thus supplementing the circulating pressure feed.

In the position of the oil pump piston shown in the drawings, one of its ports 80 is in registration with the port 79 in the cylinder 78, thus providing a path for the entrance of oil from the reservoir into the space within the hollow piston 77, and into a chamber 81 below and in communication with the interior of the piston. During the downward stroke of the piston toward the end of its travel, the port 79 in the cylinder 78 is closed, whereupon the piston produces a pressure within itself and within the chamber 81. Referring now to Fig. 9, there is a horizontal outlet passage 82 from this chamber, formed partly in the cylinder 78, partly in the housing 31, and partly in the cover-plate 38. This passage communicates with an upwardly-extending passage 83 (see Fig. 4), which in turn communicates with an annular chamber 84 in the bearing 37, thus providing a considerable amount of oil about the shaft 36, and lessening the adhesion of the shaft to the bearing, thereby offering less resistance at the moment of starting the shaft in rotation. This chamber, in turn, communicates with pairs of grooves 85 and 85' (best shown in Fig. 10) extending lengthwise of the bearing.

The grooves 85 (see left-hand end of Fig. 10) lead directly back into the chamber 32. The grooves 85' communicate with an annular groove 86 in the bearing 37 about the shaft adjacent the end of the bearing, and continue past said annular groove to the adjacent face of the thrust washer 49. To assure lubrication of the bearing surface of the thrust washer against the end of the bearing 37, the thrust washer (see Fig. 5) is provided with one or more, herein two angular grooves 87, which draw oil out of the grooves 85' and feed it to the endwise engaging surfaces.

Any oil which escapes at this point into the motor chamber 39 gravitates into a groove 88 at the bottom of the chamber, and is sucked up by the gas intake pipe 54, which, as herein shown, is provided with a wire gauze strainer 89 about its lower end. The oil which is sucked up by the gas intake conduit passes upwardly along with the gas, and is returned to the chamber 32, by way of the recess 57 (see Fig. 3). At this point, there is a slot 90 leading downwardly from the recess 57 into a passage 91 to restore oil to the annular chamber 84. This supplements the supply of oil which is pumped around through the circulating system. Referring now to Fig. 2, lubrication of the bearing surfaces of the rock-shaft is accomplished by taking oil from the annular chamber 84 through openings 92 and also from the annular groove 86 through the slot 69 to the bore 73, in which the rockshaft 61 turns in the driving shaft 36.

It will be remembered that the gas which is withdrawn from the motor chamber into the suction chamber of the pump enters the suction

chamber through the passage 56. Before this gas can pass upwardly into the passage 58 (see Fig. 6), it must pass downwardly beneath the lower edge of a vertically disposed baffle 93, and thence upwardly to the passage 58. This baffle tends to return to the bottom of the chamber 32 oil carried by the gas. An additional baffle 94, which is closed at its outer end (see Fig. 7) and is disposed beneath the passage 58, guards the latter against the entrance of oil which might otherwise be carried in that direction by the splash and the rotation of the weights 62 and 76. Another obliquely disposed baffle 95, opposite the baffle 94, prevents oil from being carried over into the space between the baffles 94 and 95 by the rotation of the weights, which is in the direction of rotation of the arrow,—i. e., clockwise. Oil caught by the baffle 95 turns back to the main body of oil, while the machine is in operation, and when it is idle. The baffles 93, 94 and 95, are conveniently made as a unit, shown in Fig. 7, with the baffle 93 in the form of a flat plate welded or otherwise appropriately secured to two arc-shaped pieces 96 and 97, on which the baffles 94 and 95, respectively, are formed. The arc-shaped piece 96 is provided with an opening 98, which registers with the passage 58 (see Fig. 6), and this opening has about it a lip 99, which tends to prevent the entrance of oil into the passage 58. In assembling the machine, the baffle unit shown in Fig. 7 is fitted into the chamber 32, and the parts 96 and 97 snugly fit the cylindrical surface of the chamber.

In addition to the means of lubrication afforded by the described circulating system and by the oil sucked up by the gas intake, there is a rather elaborate splash system which will now be described, reference being had at first to Fig. 2. The upper end of the hollow oil pump piston 77 is provided with an opening 100, through which oil is splashed upwardly onto the lower bearing surface of the sliding shoe or cross-head 34, and from this point, oil is distributed along the lower face of the shoe by radiating grooves 101 (see Fig. 8). Oil also passes through a passage 102 leading upwardly to the bearing surface of the crank-pin, and through a radial passage 103 in the latter to a longitudinal passage 104, which communicates with the bore 74 within the rock-shaft 61.

The compressor piston is lubricated by splash and mist, and the piston is provided with an opening 105 to conduct oil to its interior, whence oil gravitates through an opening 106 in the piston to a passage 107 in the sliding shoe or cross-head 34, whence oil is conducted to the bearing surface of the crankpin. The opening 106 also feeds oil to the upper bearing surface of the sliding shoe, and this oil is distributed by radiating grooves 108 similar to the grooves 101 over the sliding surfaces. The crank-pin is additionally lubricated by splash through upper and lower openings 109 provided in a hub-like extension 110 of the sliding shoe. Distribution of oil lengthwise of the crank-pin is effected by grooves 111 (see Fig. 6), formed in the shoe lengthwise of the crank-pin. Instead of providing the compressor piston with rings, the latter is provided with a series of circumferential oil grooves 112, which serve to form an oil seal between the piston and the cylinder. The lower end of the oil pump is closed by a cylinder head 113, which holds the cylinder 78 in place, the latter being provided at its lower end with a circumferential flange 114, received in a corre-

sponding recess in the housing 31. The diameter of the cylinder 78 is such that by first removing the cylinder head 113 and then the cylinder 78, the piston member, comprising the compressor piston and the oil pump piston, can be removed downwardly after being disconnected from the crank-pin by first removing the partition plate 38 with its bearing and the parts carried thereby. This of course calls for the preliminary removal of the cover-plate 40, and then the stator 43, before the partition plate 38 can be removed.

It will thus be seen that the oiling system comprises first, a circulating system including the oil pump, second, a splash system, utilizing the splash of oil due to the motion of the mechanism in the chamber 32, and, third, the utilization of the gas suction pipe as a means for riding the motor chamber of oil and utilizing this oil to supply some of the bearing surfaces. In all, the lubricating system is unusually complete and adequate to furnish ample lubrication to all working parts.

Having thus described one embodiment of the invention, but without limiting myself thereto, what I claim and desire by Letters Patent to secure is:—

1. A gas compressor and motor unit comprising, in combination, a housing presenting a motor chamber and a crank-case and suction chamber with a partition therebetween, said motor chamber having an inlet for the gas, and said partition having a passage for gas and lubricating oil from said motor chamber to said crank-case and suction chamber, said crank-case and suction chamber presenting a reservoir for lubricating oil, a compressor cylinder having a lateral, refrigerant intake port leading from said crank-case and suction chamber into said cylinder, a compressor piston working in said cylinder and covering and uncovering said port, an oil pump cylinder having a lateral, oil intake port leading from said oil reservoir into said oil pump cylinder, an oil pump piston working in said oil pump cylinder and covering and uncovering said oil intake port, an electric motor housed within said motor chamber, a crank housed within said crank-case and suction chamber, a driving shaft connecting said motor to said crank-pin to drive the latter, a bearing for said shaft supported by said partition and provided with an oil chamber about said shaft and a passage leading from said oil chamber to said crank-case and suction chamber, an oil supply conduit leading from said oil pump cylinder to said oil chamber, and baffle means to cause the separation of the oil from the gas within said crank-case and suction chamber and the return of the oil to said oil reservoir.

2. A gas compressor and motor unit comprising, in combination, a housing presenting a gas intake chamber and an oil reservoir, a gas compressor whose intake is in communication with the upper portion of said chamber, an oil pump whose intake is in communication with the lower portion of said chamber, a common driving mechanism for said compressor and said oil pump, a motor which drives said mechanism, said mechanism and said motor being housed within said housing, and means to conduct oil from said pump to said driving mechanism and to return oil to said oil pump.

3. A gas compressor and motor unit comprising, in combination, a compressor for the gas, an oil pump comprising a cylinder and a piston working therein, a common driving mechanism for said compressor and said oil pump, a motor

which drives said mechanism and a housing which houses said mechanism and said motor presenting a gas intake chamber for said compressor and an oil reservoir from which said oil pump takes oil and supplies oil to said driving mechanism, said cylinder and a portion of said piston being within said oil reservoir where they will be at least partially submerged in the oil.

4. A compressor unit comprising, in combination, a compressor for the gas, an oil pump, a common driving shaft for said compressor and said pump, a bearing for said shaft, said compressor and pump being disposed at one end of said bearing, a thrust washer carried by said shaft and engaging the other end of said bearing endwise, means to conduct oil from said pump to the engaging surfaces of said bearing and said thrust washer, and means to cause the distribution of oil on said surfaces.

5. A compressor unit comprising, in combination, a compressor for the gas, an oil pump, a common driving shaft for said compressor and said pump, a bearing for said shaft, a thrust washer carried by said shaft and engaging said bearing endwise, means to conduct oil from said pump to the engaging surfaces of said washer and said bearing, and an electric motor comprising a stator and a rotor, the latter being secured to said shaft and offset with relation to said stator in a direction opposite to said bearing to utilize the magnetic flux to urge said washer against said bearing.

6. A gas compressor and motor unit comprising, in combination, a sealed unit comprising a gas compressor having an intake chamber, a motor chamber having a gas inlet, an electric motor within said motor chamber, a driving mechanism including a shaft connecting said motor and said compressor, a bearing for said shaft, a circulatory oiling system including an oil pump which supplies oil to the bearing surfaces of said shaft and said bearing, and a gas and oil suction conduit leading from said motor chamber and delivering gas from said motor chamber to said intake chamber and oil from said motor chamber to said oiling system.

7. A gas compressor and motor unit comprising, in combination, a sealed unit comprising a gas compressor having an intake chamber, a motor chamber having a gas inlet, an electric motor within said motor chamber, a driving mechanism including a shaft connecting said motor and said compressor, a bearing for said shaft, a circulatory oiling system including an oil pump which supplies oil to the bearing surfaces of said shaft and said bearing, and a gas and oil suction conduit leading from said motor chamber and delivering gas from said motor chamber to said intake chamber and oil from said motor chamber to said oil pump.

8. A gas compressor and motor unit comprising, in combination, a sealed unit comprising a gas compressor having an intake chamber, a motor chamber having a gas inlet, an electric motor within said motor chamber, a driving mechanism including a shaft connecting said motor and said compressor, a bearing for said shaft, a circulatory oiling system including an oil pump which supplies oil to the bearing surfaces of said shaft and said bearing, said pump being disposed within said intake chamber, and a gas and oil suction conduit leading from said motor chamber and delivering gas from said motor chamber to said intake chamber and oil from said motor chamber to said oiling system.

9. A gas compressor and motor unit comprising, in combination, a sealed unit comprising a gas compressor having an intake chamber, a motor chamber having a gas inlet, an electric motor within said motor chamber, a driving mechanism including a shaft connecting said motor and said compressor, a bearing for said shaft, a circulatory oiling system including an oil pump which supplies oil to the bearing surfaces of said shaft and said bearing, said pump being disposed within said intake chamber and driven by said shaft, and a gas and oil suction conduit leading from said motor chamber and delivering gas from said motor chamber to said intake chamber and oil from said motor chamber to said oiling system. 5
10. A gas compressor and motor unit comprising, in combination, a sealed unit comprising a gas compressor having an intake chamber, a motor chamber having a gas inlet, an electric motor within said motor chamber, a driving mechanism including a shaft connecting said motor and said compressor, a bearing for said shaft, a circulatory oiling system including an oil pump which supplies oil to the bearing surfaces of said shaft and said bearing, and a gas and oil suction conduit leading from said motor chamber and delivering gas from said motor chamber to said intake chamber and oil from said motor chamber 15 to said bearing surfaces. 15
11. In a compressor unit, the combination of a compressor comprising a cylinder and a hollow piston working therein, said piston having one or more lateral openings leading thereinto to supply oil to the interior of said piston and an opening through which oil is conducted from the interior of said piston, and mechanism to drive said piston, said mechanism including a crankpin supplied with oil from the interior of said piston. 30
12. In a compressor unit, the combination of a gas compressor having a gas intake chamber the lower portion of which constitutes an oil reservoir, means to deliver gas and oil to said chamber, and means within said chamber to separate oil from the gas and to permit oil to gravitate into said reservoir. 45
13. In a compressor unit, the combination of a gas compressor having a gas intake chamber the lower portion of which constitutes an oil reservoir, means to deliver gas and oil to said chamber, and a baffle within said chamber to cause oil to be separated from the gas and allowed to gravitate into said chamber. 50
14. In a compressor unit, the combination of a gas compressor comprising a gas intake chamber the lower portion of which constitutes an oil reservoir, said compressor comprising a cylinder having a lateral intake port, and a piston working in said cylinder and covering and uncovering said port, and means within said chamber to deflect oil from said port. 55
15. In a compressor unit, the combination of a gas compressor comprising a gas intake chamber the lower portion of which constitutes an oil reservoir, said compressor comprising a cylinder having a lateral intake port, and a piston working in said cylinder and covering and uncovering said port, and a plurality of baffles within said chamber to deflect oil from said port. 65
16. In a compressor unit, the combination of a gas compressor comprising a gas intake chamber the lower portion of which constitutes an oil reservoir, said compressor comprising a cylinder having a lateral intake port, a piston work- 75
- ing in said cylinder and covering and uncovering said port, mechanism to drive said piston, said mechanism including a part rotating within said chamber, and a baffle within said chamber and arranged to guard said port from oil thrown off by said rotating part. 5
17. In a compressor unit, the combination of a gas compressor having a gas intake chamber the lower portion of which constitutes an oil reservoir, said compressor having an intake port leading from said chamber, means to conduct gas and oil into said chamber, and means to cause oil entering said chamber to be directed downwardly into said reservoir while allowing gas free from oil to enter said intake port. 10 15
18. In a compressor unit, the combination of a gas compressor having a gas intake chamber the lower portion of which constitutes an oil reservoir, said compressor having an intake port leading from said chamber, means to conduct gas and oil into said chamber, and a baffle extending downwardly below said intake port to cause oil and gas entering said chamber to be directed downwardly and the oil allowed to gravitate into said reservoir while the gas rises to said intake 20 port. 25
19. A gas compressor unit comprising, in combination, a compressor for the gas, an oil pump comprising an oil displacing member and a chamber from which said member displaces oil, a common driving mechanism for said compressor and said member, said mechanism including a driving shaft and a bearing for said shaft, a housing presenting a gas intake for said compressor and an oil reservoir from which said chamber receives oil, and a conduit disposed externally of said member and leading from said chamber directly to bearing surfaces of said bearing and said shaft. 30 35
20. A gas compressor unit comprising, in combination, a compressor for the gas, an oil pump comprising an oil displacing member and a chamber from which said member displaces oil, a common driving mechanism for said compressor and said member, said mechanism including a driving shaft and a bearing for said shaft, said bearing being provided with a reservoir about said shaft, a housing presenting a gas intake chamber for said compressor and a main reservoir from which said chamber receives oil, and a conduit disposed externally of said member and leading from said chamber directly to the first-mentioned reservoir. 40 45 50
21. A gas compressor unit comprising, in combination, a compressor for the gas, an oil pump comprising an oil displacing member and a chamber from which said member displaces oil, a common driving mechanism for said compressor and said member, said mechanism including a driving shaft and a bearing for said shaft, said bearing having an end thrust-receiving surface, a housing presenting a gas intake for said compressor and an oil reservoir from which said chamber receives oil, and a conduit disposed externally of said member and leading from said chamber to said thrust-receiving surface. 55 60 65
22. A gas compressor unit comprising, in combination, a compressor for the gas, an oil pump comprising an oil displacing member and a chamber from which said member displaces oil, a common driving mechanism for said compressor and said member, said mechanism including a driving shaft and a bearing for said shaft, said bearing being provided with a reservoir about said shaft, a thrust-receiving surface and a conduit 70 75

leading from said reservoir to said surface, a housing presenting a gas intake for said compressor and an oil reservoir from which said chamber receives oil, and a conduit disposed externally of said member and leading from said chamber to the first-named reservoir.

23. A gas compressor unit comprising, in combination, a compressor for the gas, an oil pump comprising an oil displacing member and a chamber from which said member displaces oil, a common driving mechanism for said compressor and

said member, said mechanism including a driving shaft and a bearing for said shaft, said bearing being provided with a reservoir about said shaft, thrust-receiving surfaces and conduits leading from said reservoir in opposite directions to said surfaces, a housing presenting a gas intake for said compressor and an oil reservoir from which said chamber receives oil, and a conduit disposed externally of said member and leading from said chamber to the first-named reservoir.

WILLIAM D. DRYSDALE.
